JAMES F. SPENCE, OF BROOKLYN, NEW YORK, AND LOVIAS D. TOWSLEY
OF NEWARK, NEW JERSEY.

Letters Patent No. 99,274, dated January 25, 1870.

IMPROVED APPARATUS FOR CARBURETTING AIR.

The Schedule referred to in these Letters Patent and making part of the same.

To all whom it may concern:

Be it known that we, JAMES F. SPENCE, of Brooklyn, in the county of Kings, and State of New York, and LOVIAS D. TOWSLEY, of Newark, in the county of Essex, and State of New Jersey, have invented certain new and useful Improvements in Carburetters; and we do hereby declare that the following is a full, clear, and exact description thereof, reference being had to the accompanying drawings, which make part of the same, and in which—

Figure 1 represents a view, in perspective, of a carburetter embracing our improvements.

Figure 2 is a vertical section of the same.

Figure 3 represents a horizontal section through the gas-supplying reservoir, at the line $z z$ of fig. 2.

Figure 4 represents a horizontal section of the apparatus, at the line $y y$ of fig. 2.

Our invention relates to an apparatus for carburetting air, applicable to gas-machines; and consists in the construction of the carburetter in such manner as that the hydrocarbon-fluid will be supplied to the vaporizing action of the air in certain specific quantities, whereby we are enabled to utilize the entire body of hydrocarbon-fluid until the supply is consumed, and thus prevent the loss of a large proportion of the fluid, as is the case with carburetters heretofore constructed.

In the accompanying drawings—

A is a cylindrical case, of any suitable dimensions, closed at both ends and hermetically sealed, within which is enclosed the tank B, for containing the hydrocarbon-fluid. This tank rests upon the bottom of the enclosing-case A, and may be fixed or removable, at pleasure, and is of such dimensions as to leave an annular carburetting-chamber, C, extending from the bottom of the enclosing-case to the top of said tank, and a chamber, D, of equal area with the case, above the tank, for the purpose of receiving, holding, and supplying the gas to the burners, which latter is done by means of a distributing-pipe, E. The tank is filled with the hydrocarbon-fluid, and the annular carburetting-chamber C of the enclosing case is for the purpose of receiving from the said tank, so much of the hydrocarbon-fluid as is required for use, which is, at all times, a regular given quantity.

The interior supply-tank B is provided with a supply-pipe, F, at its upper end, communicating with an opening in the top of the enclosing-case, through which the tank is filled, and this opening is closed by a screw-cap, G, or any other suitable device.

The tank is also provided with a vertical tube, H, extending within a suitable distance of the bottom thereof, while its upper end communicates with the gas-supply chamber D. This tube H is for the pur-

pose of equalizing the pressure upon the fluid within the tank, and insures a proper flow therefrom into the annular carburetting-chamber C, through a pipe, I, at the bottom thereof, by a branch, J, extending through the enclosing-case A, communicating with said annular chamber C, and provided with a stop-cock, K, or its equivalent. This stop-cock is necessary, in order to cut off communication between the tank B and the annular chamber, when the tank is being filled, but is subsequently opened, and remains so to allow the annular chamber to be regularly supplied. This communicating-tube I J must be on a level with the lower opening of the tube H, in the tank, and it is by this means that we are enabled to supply the annular chamber C with a given quantity of hydrocarbon-fluid, which is equal in depth to the space between the bottom of the case and the lower opening of said tube, and this quantity in thus limited the moment the fluid rises sufficiently in the chamber to seal the opening in the tube J, and is, at all times, the only portion of the fluid exposed to the vaporizing action of the air, leaving the bulk of the material protected from such action, as shown in fig. 2, thus enabling us to use the entire quantity until the tank is emptied, thereby effecting a great saving of material, which is lost, to a great extent, when the whole of said material is exposed.

In order to increase or diminish the quantity of hydrocarbon thus exposed, the vertical tube H is made adjustable, so as to increase or diminish the distance between its lower open end and the bottom of the tank B, and thus increase or diminish the flow of said material into the outer annular chamber. This adjustment is effected by a rod, a, passing through a stuffing-box on the top of the case, and connected to the upper open end of the tube H, which may also pass through a stuffing-box in the top of the tank. The rod may have a screw-thread thereon, or may be held in position by the packing of the stuffing-box.

The top of the annular chamber C is formed by an annular plate, L, hermetically sealed to the top of the tank B, from which depends, a suitable distance, a series of tubes, M, communicating with the said annular chamber C, and also with the upper gas-supplying chamber D. They may be of any suitable number, and are for the purpose of conducting the gas from the carburetting-chamber C to the supply-reservoir D, and may be filled with any suitable material which will conduct, by capillary attraction, the gas to the supply-chamber.

As the carburation of the air is effected in the annular chamber C, in order to increase the carburetting-surface of this chamber, it is provided with a corrugated or fluted cylinder, N, of any suitable material, such as

wire gauze, &c., arranged so as to enclose the series of pendent vertical tubes M, by which the entire space of said chamber is utilized.

The air-supply pipe O, from the air-pump or wheel, enters the gas-supply chamber D, and extends vertically a suitable distance into the annular carburetting-chamber C, through which pipe O the said chamber is supplied with a constant and regular flow of air.

The carburetting-chamber C is supplied with one or more stop-cocks, P Q, for the purpose of drawing off the fluid whenever it shall become necessary or expedient, or to determine the quantity of the fluid therein.

If it may be deemed advisable, instead of the adjustable vertical tube of the tank, it may be provided with a coil.

Having described our invention,

We claim—

1. The carburetter, having a fixed interior supply-tank, B, and a fixed surrounding carburetting-chamber, C, surmounted by the gas-supply reservoir D, all arranged in the same vessel, communicating with each other, and operating in the manner and for the purpose herein described and shown.

2. The tube I J, arranged at the bottom of the supply-tank, so as to communicate directly with the bottom of the annular carburetting-chamber C, in combination

with the supply-tube H, for the purpose of supplying only so much of the hydrocarbon to be vaporized, as is equal in depth to the distance between the open end of said tube H and the bottom of the tank, as herein described and shown.

3. The series of vertical tubes M, in combination with the annular carburetting-chamber C, the corrugated open cylinder N, and the gas-supply reservoir D, arranged in the manner and for the purpose herein described and shown.

4. The tube H, connected to and made adjustable within a fixed supply-tank, B, for the purpose of regulating the quantity of the hydrocarbon within the carburetting-chamber, irrespective of the supply in the tank, as herein described and shown.

5. The combination of the enclosing-case A, the interior hydrocarbon-tank B, the annular carburetting-chamber C, the gas-supply reservoir D, the equalizing-tube H, and the communicating-pipe I J, the whole constructed, arranged, and operating substantially as before described.

JAMES F. SPENCE.
LOVIAS D. TOWSLEY.
